UNITED STATES PATENT OFFICE.

JOSEPH W. SCHAROLD, OF CINCINNATI, OHIO, ASSIGNOR TO THE RUDOLPH WURLITZER MANUFACTURING COMPANY, OF NORTH TONAWANDA, NEW YORK, A CORPORATION OF NEW YORK.

CONTROLLING DEVICE FOR AUTOMATIC MUSICAL INSTRUMENTS.

1,124,814.

Specification of Letters Patent.

Patented Jan. 12, 1915.

Application filed August 30, 1910. Serial No. 579,693.

To all whom it may concern:

Be it known that I, JOSEPH W. SCHAROLD, a citizen of the United States, residing at Cincinnati, in the county of Hamilton and State of Ohio, have invented new and useful Improvements in Controlling Devices for Automatic Musical Instruments, of which the following is a specification.

This invention relates to a controlling device for automatic musical instruments and other devices or machines which are operated by a coin-controlled electric motor.

When such instruments are installed in halls or other public places, it is customary 15 to place coin-receptacles or so-called "slot-boxes" at tables or other convenient stations, so that the instrument can be played from different parts of the hall. Such receptacles include a chute containing switch terminals of the motor-circuit which are bridged upon the deposit of a nickel or other proper coin, closing the circuit and causing the instrument to play a selection. It sometimes happens that persons at different tables or stations deposit coins at about the same time or during the playing of a piece, in which case the instrument plays but a single selection, instead of two or more according to the number of coins deposited.

30 The object of my invention is the provision of a simple and reliable controlling device which will practically insure the playing of a selection for every coin deposited in any of the several boxes, giving all patrons full value for their deposits.

In the accompanying drawings consisting of 2 sheets: Figure 1 is a front elevation of the improved controlling device associated with the coöperating parts of a self playing 40 musical instrument, such parts being shown in section. Fig. 2 is a fragmentary face view of the perforated music sheet, showing the controlling perforations. Figs. 3 and 4 are sectional front elevations of the device, showing different positions of the switch-operating slide. Fig. 5 is a rear view of the device. Fig. 6 is a longitudinal section on line 6—6, Fig. 3. Figs. 7 and 8 are cross sections on the correspondingly-numbered 50 lines in Fig. 3.

Similar letters of reference indicate corresponding parts throughout the several views.

A indicates the electric motor of the self-

playing musical instrument or other machine or apparatus to be controlled. The motor circuit is controlled by a switch of any suitable construction, that shown in the drawings comprising a pair of bolts *b*, *b*, forming the terminals of the motor circuit and passing respectively through stationary, insulated cups or receptacles *c* containing mercury or other conductive fluid, and a vertically-movable cross-head *D* carrying a metallic staple *d*, the legs of which when lowered into the two mercury cups close the motor-circuit, as shown in Figs. 3, 4 and 5, while when raised out of contact with the mercury, break said circuit, as shown in Fig. 1. The mercury cups are covered by a plate *c* having openings for the passage of the staple legs. The cups are formed in a non-conductive strip or block *C* secured by the bolts *b* to a non-conductive back plate *C* which in turn is suitably fastened to the wall of the musical instrument or other support. Secured to the front side of said back plate is an upright frame *E* having vertical ways *e* in which is guided a slide *F* which operates the switch cross head *D*. This slide is preferably composed of side bars *f* and upper and lower cross bars *f*¹, *f*², forming practically a longitudinally-slotted slide. Projecting into the slot of the slide is a lip *d*¹ formed at the upper end of a vertical bar *d*² which carries the cross head *D*. The relation of the lip *d*¹ to the lower cross bar *f*² is such that when the slide is raised to its highest position, as shown in Fig. 1, said cross bar engages the lip lifting the switch cross head *D* and breaking the motor circuit, while when the slide occupies any other position its lower cross bar is more or less removed from the lip, allowing the cross head to remain in its lowermost position in which the motor circuit is closed.

As shown, the side bars of the slide are provided at their inner edges with ratchet teeth *f*³, *f*⁴ respectively, the teeth of the two bars facing in opposite directions. These opposing rows of teeth are engaged alternately by a double-ended detent-pawl *g*, carried by the shank *g*¹ of a magnet-armature *G*, so that whenever the armature is attracted and released, the slide *F* is allowed to drop the distance of one tooth, the toothed bars and the detent pawl constituting an escapement. The shank *g*¹

2
slides transversely of the slide F and is guided in a horizontal groove g^2 formed in the front side of the upright frame E, as best shown in Fig. 6.

5 H indicates the electromagnet co-operating with the armature G, and i a spring for withdrawing the latter when the magnet is de-energized. This magnet is included in a coin-controlled circuit containing a plurality of coin-boxes the switch-contacts of which are shown diagrammatically at j , j' , in Fig. 1. These coin-boxes, which are not shown in the drawings, are placed at different tables or stations, as before-stated, and the coin-contacts of the several boxes are connected in parallel, as shown, so that the magnet circuit will be closed by the deposit of a proper coin in any one of the coin-boxes, the coins dropping between the contacts and connecting them momentarily, so as to quickly make and break the circuit and attract and release the armature once for every coin deposited in any one of the boxes.

The slide F is raised intermittently by a 25 spring-pressed feed-pawl k engaging its downwardly-facing ratchet teeth and mounted on a vertically-reciprocating bar or carrier K guided in a groove k^1 in the front side of the frame E. The downward stroke of the bar K is limited by a pin or stop l projecting from the bottom of the groove k^1 , toward which pin it is constantly urged by a spring l^1 connecting the bar with the frame E.

35 The feed pawl is preferably pivoted to the bar K and constantly swung toward the teeth of the slide F by a spring k^2 . In the normal depressed position of said bar, the pawl is held clear of said teeth by a stop or pin m projecting from the frame E into the slot of the slide, as shown by full lines in the drawings. This construction prevents the feed pawl from checking the descent of the slide when the armature-detent 40 g is actuated. A stop or shoulder k^3 on the bar K is arranged to strike a cross bar e^1 of the frame E, so as to limit each upward stroke of the slide to the distance of one of its teeth.

45 In the construction shown in the drawings, the bar or carrier K is reciprocated by a motor pneumatic N controlled by the pneumatic action of the musical instrument to which the improved controlling device 50 is applied. This pneumatic action may be of any suitable type, that shown in the drawings by way of example being constructed as follows:

o indicates the usual perforated music sheet, O the tracker board and P the wind chest having the usual exhaust chamber p .

R indicates a valve chamber communicating with said exhaust chamber by a port r and with the outer atmosphere by a port r^1 .

65 These ports are controlled by valves r^2 , r^3

carried by a stem which is moved in one direction by a spring r^4 and in the opposite direction by the customary pouch or pneumatic r^5 , the pouch chamber being connected with the corresponding tracker duct by a 70 channel s and tube s^1 . A port t connects the motor pneumatic with the valve chamber. The operation of this pneumatic action is well understood; the motor pneumatic N being collapsed and caused to elevate the slide F when one of a series of controlling perforations o^1 , o^2 &c., of the music sheet register with the companion tracker duct, and said pneumatic being flushed when said duct is closed by imperforate portions 80 of the sheet, allowing the pawl carrier K to descend to its initial position. Said controlling perforations are so spaced that the motor pneumatic is collapsed at the end of each selection on the sheet, or any other predetermined stages or intervals.

85 The operation of the controlling device is as follows: Normally, the slide F is in its highest or initial position, as shown in Fig. 1. In this position, the switch cross head D is elevated and the motor circuit is broken, the cross head being suspended from the lower cross bar f^2 of the slide by the lip d^1 . When a coin is deposited in any of the slot-boxes, hereinbefore referred to, the magnet H is momentarily energized, thus reciprocating the detent pawl g of the escapement and allowing the slide to drop the distance of one tooth. This movement of the slide permits the switch cross head to drop far enough to close the motor circuit, and the instrument begins to play the first selection on the music sheet. If no additional coins are deposited in any of the coin-boxes during the playing of that selection, the 95 motor pneumatic N is deflated at the end of the selection by the registration of the first controlling perforation o^1 with the corresponding tracker duct, thereby elevating the slide to its former position, raising the 100 switch cross head sufficiently to break the motor circuit and stopping the instrument. If, however, a second coin is deposited in one of the coin-boxes during the playing of the first selection, the armature G is reciprocated a second time and the slide drops the distance of another tooth, leaving the 105 depressed switch cross-head undisturbed and removing the lower cross bar of the slide two steps or teeth from the lip d^1 of the said cross head. Under these conditions, after the playing of the first selection, the motor pneumatic N is deflated and the slide 110 is again elevated one tooth, as before described, but since the slide was dropped or allowed to recede the distance of two teeth, its lower cross bar f^2 stops short of said lip and the switch cross head is therefore allowed to remain in its depressed position. 115 The instrument now plays the second selec- 120 125 130 135

tion on the music sheet, and at the end thereof, the second controlling perforation o^2 comes into action and causes the motor pneumatic to be deflated a second time. The slide is thereby raised a second step or tooth which is sufficient to cause its lower cross bar f^2 to engage the lip d^1 and raise the switch cross head, thus stopping the instrument at the ends of the second selection.

- 10 Should additional coins be deposited at other tables or stations during the playing of either of said selections, the slide will be lowered a corresponding number of teeth. Its lower cross bar thus retreats one step 15 from the lip d^1 for each coin deposited and the slide is raised one step at the end of each selection but does not engage said lip and open the motor switch until a selection has been played for the last coin deposited. 20 The controlling device thus insures the playing of a selection for every coin deposited.

In the position of the parts shown in Fig. 4, the slide has been dropped the distance of one tooth,—just far enough to close 25 the motor switch, while in the position shown in Fig. 3, the slide has been dropped the distance of five teeth and the switch will therefore be opened after the instrument has played five selections.

30 The construction of the controlling device may obviously be modified within the scope of the appended claims, and I do not therefore wish to be limited to the particular construction herein shown and described.

35 In the drawings, four mercury cups c and a like number of terminal bolts b are shown. Two of these form the terminals of the motor circuit, as hereinbefore described, while the remaining two may be used as terminals of an electric light circuit for illustrating the musical instrument to which the controlling device is applied, or for any other desired purpose.

40 I claim as my invention:

1. In a device of the character described, the combination of a switch having a shifting member, a controlling member arranged to engage said shifting member and movable relatively thereto to recede different distances therefrom, means controlling the receding movement of said controlling member, and means for intermittently advancing said controlling member.

45 2. In a device of the character described, the combination of a switch having a shifting member, a controlling member arranged to engage said shifting member and movable relatively thereto to recede different distances therefrom, a controlling circuit, electro-magnetic means included in said circuit and controlling the receding movement of said controlling member, and means for intermittently advancing said controlling member.

50 3. In a device of the character described,

the combination of a switch having a shifting member, a controlling member arranged to engage said shifting member and movable relatively thereto to recede different distances therefrom, a detent device controlling the receding movement of said controlling member, a controlling circuit, an electromagnet included in said circuit and controlling said detent, and means for intermittently advancing said controlling member.

4. In a device of the character described, the combination of a slide having a longitudinal slot, means for intermittently advancing the slide, a detent device for controlling the retreating movement of the slide, means for actuating the detent device, and a switch having a shifting member which engages the slot of the slide.

5. In a device of the character described, the combination of a slide having a longitudinal slot, means for intermittently advancing the slide, a detent device for controlling the retreating movement of the slide, means for actuating the detent device, a switch, and an operating bar for the switch having a lip arranged in said slot.

6. In a device of the character described, the combination of a support, a slide guided thereon and having a pair of opposing toothed bars, a reciprocating detent-pawl coöperating with said toothed bars and movable transversely thereof, an electromagnet and an armature for actuating said detent, a reciprocating carrier slidable lengthwise of the slide, a feed pawl mounted on said carrier and arranged to engage the teeth of the slide, means for actuating the carrier, and a switch operatively connected with said slide, said slide being capable of receding independently of said switch.

7. In a device of the character described, the combination of a support having longitudinal guides, a longitudinal groove arranged between said guides and a transverse groove, a slide arranged in said guides and having a longitudinal slot, the opposing longitudinal edges of said slot having teeth, a reciprocating detent-pawl guided in said transverse groove and adapted to engage said teeth, a reciprocating carrier-bar guided in said longitudinal groove, a feed pawl carried by said carrier-bar and adapted to engage said teeth, means for actuating said carrier-bar and said detent-pawl, and a switch operatively connected with said slide.

8. In a device of the character described, the combination of a switch, a support, a slide operatively connected with said switch and guided on said support, the slide having a longitudinal slot the longitudinal edges of which are provided with teeth, a detent device coöperating with said teeth, a carrier mounted on said support and mov-

4
able lengthwise of said slide, a feed pawl mounted on said carrier within said slot and arranged to engage said teeth, a stop arranged to hold the feed pawl out of engagement with the toothed slide in the depressed position of the carrier, and means for actuating said detent device and said carrier.

9. In a device of the character described, 10 the combination of a switch comprising a pair of insulated receptacles adapted to contain a conductive fluid, circuit-terminals extending into said receptacles and a movable head carrying electrically-connected

contacts arranged to enter said receptacles, 15 a slide operatively connected with said switch-head but capable of limited idle movement toward said receptacles, means for intermittently advancing the slide, and intermittently-acting means for controlling 20 the idle or receding movement of the slide.

Witness my hand this 25th day of August, 1910.

JOS. W. SCHAROLD.
